CLAIM

The ornamental design for a beverage can holder, as shown and described.

DESCRIPTION

FIG. 1 is a top front perspective view of a beverage can holder, showing my new design.

FIG. 2 is a bottom rear perspective view of the beverage can holder.

FIG. 3 is a front elevational view of the beverage can holder.

FIG. 4 is a rear elevational view of the beverage can holder.

FIG. 5 is a left side elevational view of the beverage can holder.

FIG. 6 is a right side elevational view of the beverage can holder.

FIG. 7 is a top plan view of the beverage can holder; and,

FIG. 8 is a bottom plan view of the beverage can holder. The beverage can holder is shown with two symbolic breaks in its length, and three symbolic breaks in its height. The appearance of any portion of the article between the break lines forms no part of the claimed design. Features illustrated in broken lines form no part of the claimed design.

1 Claim, 8 Drawing Sheets
